(57) **CLAIM**

The ornamental design for material handling device handle as shown and described.

DESCRIPTION

FIG. 1 is a perspective view of a material handling device handle showing our new design;

FIG. 2 is a rear elevational view thereof;

FIG. 3 is front elevational view thereof;

FIG. 4 is a left-side elevational view thereof;

FIG. 5 is right-side elevational view thereof;

FIG. 6 is a top view thereof;

FIG. 7 is a bottom view thereof; and,

FIG. 8 is a perspective view of a material handling device handle incorporating our new design.

The broken lines in the drawings depict portions of the material handling device handle that form no part of the claimed design.

1 Claim, 8 Drawing Sheets
